UNITED STATES PATENT OFFICE.

EDWARD C. MEIER, OF PHOENIXVILLE, PENNSYLVANIA.

BAFFLE CONSTRUCTION FOR BOILERS.

1,259,654.

Specification of Letters Patent. Patented Mar. 19, 1918.

Application filed April 4, 1917. Serial No. 159,840.

To all whom it may concern:

Be it known that I, EDWARD C. MEIER, a citizen of the United States, residing at Phoenixville, in the county of Chester and State of Pennsylvania, have invented certain new and useful Improvements in Baffle Construction for Boilers, of which the following is a specification.

My invention consists of an improved baffle construction for boilers. One object of my invention is to provide a baffle for boilers which will effectively operate to cause the hot gases and other products of combustion to pass adjacent to and impact with the water-containing elements of the boiler.

Another object is to so construct my invention that it can be conveniently formed and located between the units of a multiple unit boiler and will confine the heat directly to the boiler units.

A further object is to so shape my improved baffle that it will add to the strength of the supporting structure of the boiler and will also serve to help support the boiler.

These objects, and other advantageous ends which will be described hereinafter, I attain in the following manner, reference being had to the accompanying drawing in which

Figure 1 is a sectional elevation of an upright multiple unit water tube boiler having my improved baffle connected therewith, and Fig. 2 is a fragmentary detail sectional elevation of a baffle which forms a part of my invention.

Referring to the drawing, 1 represents the boiler casing having an outlet passage 2 formed in the rear thereof to permit the products of combustion to pass outwardly to the flue 3.

A pedestal 4 is located within the casing and between this pedestal and the front wall 5, is located the grate 6 which may be of any suitable construction, and as illustrated has a stepped upper surface 7 which forms the fuel supporting surface.

Two boiler units 8 and 9 are arranged within the casing 1, the boiler unit 8 comprising a plurality of water tubes 10 connecting at their top and bottom with drums 11 and 12. The boiler unit 9 includes a plurality of tubes 13 which connect at their top and bottom with drums 14 and 15.

The drums 11 and 14 are connected by a row of tubes 16, and the drums 12 and 13 are connected by tubes 17, it being noted

that the tops of the drums 11 and 14 are also connected by a tube 18 which acts as an equalizing tube between the steam spaces of the drums 11 and 14.

The drum 14 has a main steam pipe 19 leading therefrom, and the drums 12 and 15 have blow-off pipes 20 and 21 connecting therewith. The drums 11, 12, 14, and 15, are arranged horizontally and supported within the side walls, the drum 12 being further supported by the pedestal 4.

The drums 11 and 12 are in different vertical planes so that the tubes 10 extend at an incline toward the front wall 5 of the casing. This is also true of the drums 14 and 15 so that the tubes 13 also extend at an incline and substantially parallel with the tubes 10 of the boiler unit 8.

A baffle 22 is provided between the tubes 10 and extends upwardly from the drum 12 throughout a portion of the length of said latter tubes, stopping short of the drum 11 so as to provide a passage 23 between it and the drum 11.

Another baffle 23 is arranged between the tubes 13 of the boiler unit 9 and extends upwardly from the drum 15 and stops short of the drum 14 to provide a passage 24 between the upper end of the baffle 23 and the drum 14.

An intermediate baffle 25 has a portion 25a positioned between the tubes of the boiler units 8 and 9 and at its top end engages the drum 14 and extends in a substantially vertical direction to the rear tubes of the boiler unit 8. This baffle 25 then passes downwardly along the rear tubes of said boiler unit 8 and at its lower end turns and extends in a substantially vertical direction to engage the top beveled surface 26 of the pedestal 4. This latter mentioned vertical portion of the baffle 25 is provided with an opening 27 through which the tubes 17 extend and thus permits communication or passage of the products of combustion between the drums 12 and 15, the rear tubes of the boiler unit 8, the forward tubes of the boiler unit 9, and the tubes 17.

A portion 28 of the baffle 25 extends from the pedestal 4 into engagement with the drum 15, thus forming a closure for the products of combustion to confine them to the boiler units. The portion 28 has a clean out hole 31 normally closed by a door 32. A comparatively low wall 33 can if desired, be mounted directly below the drum 15 and

provided with a chamber 34 into which the blow-off pipe 21 extends. Cleaning doors 35 and 36 are provided in the side wall of the boiler casing to permit the removal of 5 the dirt from the floor under the hole 31 and in front of the rear wall of the boiler casing.

In operation, the products of combustion pass upwardly from the fire box 29 into contact with the tubes 10 of the boiler unit 8 10 which are forward of the baffle 22. They then pass through the passage 30 provided between the top of the baffle 22 and the drum 11, and by engagement with the baffle 25 are compelled to pass downwardly between the baffle 22 and the baffle 25 to heat the rear tubes of the boiler unit 8. They 15 then engage the drum 12 and pass through the opening 27 to heat the tubes 17 and drum 15. The products of combustion then pass upwardly between the rear of the baffle 25 20 and the baffle 23 to heat the forward tubes of the boiler unit 9 after which they pass through the passage 24 and downwardly between the rear of the baffle 23 and the rear 25 wall of the casing 1 and eventually pass out through the passage 2 which is located adjacent the bottom of the boiler casing and then to the flue 3.

It will thus be noted that by the inclusion 30 of my improved intermediate baffle 25, the products of combustion are confined to the elements of the boiler which contain water to be converted into steam. Furthermore, the baffle 25 serves to reinforce the 35 boiler casing. The opening 27 permits the direct passage of the products of combustion from the elements of one boiler unit to the elements of the other boiler unit without chance of their escape to other parts of the 40 boiler casing prior to their passage out of the casing. In other words, while the products of combustion are extremely hot, they are confined to the water containing elements of the boiler and thus effectively operate 45 to convert the water into steam.

It will be further noted that in the construction illustrated in the drawing, the flame and products of combustion pass upwardly and substantially parallel with the 50 water circulation in the front tubes 10, and then downwardly along the rear tubes 10 and again upwardly adjacent the front tubes 13, and finally pass downwardly adjacent the rear tubes 13. In other words, the 55 flame and products of combustion are always going with the circulation of the water within the tubes by the arrangement of baffling as illustrated. The portion 28 of the baffle 25 forms a pocket and a deflector 60 for the products of combustion between the lower drums of the units.

While I have described my invention as taking a particular form, it will be understood that the various parts of my invention 65 may be changed without departing

from the spirit thereof, and hence I do not limit myself to the precise construction set forth, but consider that I am at liberty to make such changes and alterations as fairly come within the scope of the appended 70 claims.

Having thus described my invention, what I claim as new and desire to secure by Letters Patent is:

1. The combination with a boiler having a 75 plurality of units, each unit having an upper and a lower drum, and two sets of tubes, one set communicating with the upper and lower drums of one unit, the other set communicating with the upper and lower drums 80 of the other unit, of a baffle extending from the upper drum of one of the units to the lower drum of the other of the units and having a portion extending from the latter mentioned drum to the lower drum of said 85 first mentioned unit, other baffles spaced from both sides of said first baffle to cause the products of combustion to move between them and said first baffle and to include certain of said tubes between them and said first 90 baffle, said first baffle having an opening in alinement with said lower drums, said portion of the first baffle providing a barrier for directing the products of combustion, after they pass through said opening from one side 95 of the first baffle, upwardly through the space between the other side of the first baffle and the adjacent one of said second mentioned baffles, substantially as described.

2. The combination with a boiler having a 100 plurality of units, each unit having an upper and a lower drum, and two sets of tubes, one set communicating with the upper and lower drums of one unit, the other set communicating with the upper and lower drums of the 105 other unit, of a baffle extending from the upper drum of one of the units to the lower drum of the other of the units and having a portion extending from the latter mentioned drum to the lower drum of said first mentioned unit, other baffles spaced from both 110 sides of said first baffle to cause the products of combustion to move between them and said first baffle and to include certain of said tubes between them and said first baffle, 115 said first baffle having an opening in alinement with said lower drums, said portion of the first baffle providing a barrier for directing the products of combustion, after they pass through said opening from one side of 120 the first baffle, upwardly through the space between the other side of the first baffle and the adjacent one of said second mentioned baffles, said portion of the first baffle having a clean-out opening therein and a door for 125 normally closing said clean-out opening, substantially as described.

3. A boiler including two units, each unit having an upper and a lower drum, two sets of tubes, one set communicating with the 130

upper and lower drums of one unit, the other set communicating with the upper and lower drums of the other unit, a baffle extending longitudinally between the units and 5 having an opening adjacent the bottom drums, and other baffles between the tubes of the respective units, one extending upwardly from the bottom drum of each unit toward but stopping short of the upper 10 drum of that unit to provide passages, substantially as described.

4. A boiler including two units, each unit having upper and lower drums, two sets of tubes, one set communicating with the upper and lower drums of one unit, the other set 15 communicating with the upper and lower drums of the other unit, a baffle extending longitudinally between the units, other baffles, one extending between the tubes of 20 each unit, said first baffle having an opening adjacent similarly located drums of said units, said second baffles being arranged to provide passages between the tubes at positions within the length of the units and located at positions remote from said first passage, substantially as described.

5. The combination in a water tube boiler including two units, each of said units including two drums arranged respectively at 25 their opposite ends, and tubes establishing communication between the drums of each unit, a baffle extending longitudinally be-

tween the units and having an opening, and other baffles located between the tubes of said units respectively, said opening in the first- 35 mentioned baffle being in line with adjacent drums of the units, said other baffles extending from said latter mentioned drums partway of the distance between said drums and the other drums of the units, substantially 40 as described.

6. The combination in a water tube boiler including two units, each of said units including drums respectively at their opposite ends, and tubes establishing communication 45 between the drums, a baffle extending longitudinally between the units and having an opening therein, and other baffles located between the tubes of said units respectively, said opening in the first-mentioned baffle 50 being in line with adjacent drums of the units, said other baffles extending from said latter mentioned drums partway of the distance between the latter drums and the other drums of the units, substantially as de- 55 scribed.

In testimony whereof I have signed my name to this specification in the presence of two subscribing witnesses.

EDWARD C. MEIER.
